UNITED STATES PATENT OFFICE

FRANK J. DOBROVOLNY, OF NIAGARA FALLS, NEW YORK, ASSIGNOR, BY MESNE ASSIGNMENTS, TO THE ROESSLER AND HASSLACHER CHEMICAL COMPANY, OF NEW YORK, N. Y., A CORPORATION OF DELAWARE

ODORANT FOR REFRIGERATION

No Drawing. Application filed January 2, 1930, Serial No. 418,166. Renewed September 10, 1931.

This invention relates to the use of an agent for warning of escape of refrigerant from refrigerating systems and more particularly from systems in which relatively 5 inodorous refrigerants are used. If leaks occur in large refrigerating systems, such as multiple-unit, direct expansion installations in apartment houses, relatively high and dangerous concentrations of refrigerant in 10 the air may result. If the refrigerant is not readily detected by its odor, persons breathing air containing it may not become aware of such leaks.

The object of my invention is to make possible 15 the detection of leaks in refrigerating systems operating with relatively inodorous refrigerants by incorporating in the refrigerant a small proportion of one or more of the alkyl mercaptans, substances having strong, 20 unpleasant odors.

Substances having odorous or irritating properties have heretofore been incorporated in gases to enable their detection. Practically any stable odorant or irritant with a sufficiently 25 high vapor pressure may be used for such purpose. However, for use in a refrigerant, such a warning agent must possess special properties. It must not only have an appreciable vapor pressure at room 30 temperature, but must also be readily soluble in the refrigerant at the lowest temperature occurring in the refrigerating system, have a freezing point below this temperature, be stable under conditions occurring in the system, 35 have little or no corrosive effect on metals and must not react with the refrigerant.

I have found that alkyl mercaptans possess properties which make them especially 40 suited for warning agents in refrigerating systems. The proportions I have used range from about 0.5% to 2.0% by weight of mercaptan in the refrigerant in the condensed or liquid state. This invention is, however, 45 not limited to these proportions, as it is conceivable that other proportions would be satisfactory, especially under conditions other than those occurring in my experiments.

50 In general, the best proportions for warn-

ing purposes depends on the nature of the refrigerant and the type of refrigerating machine. It may be desirable to produce a stronger warning effect with some refrigerants than with others and this may be done 55 by increasing the mercaptan content. Various types of refrigerating systems may require different proportions of the warning agent. The proportions I prefer to use in a direct expansion refrigerating system are 60 0.5-1.0% by weight of alkyl mercaptan in the refrigerant. The mercaptan may be introduced in any suitable manner, either before or after charging the system with refrigerant. 65

Refrigerants with which alkyl mercaptans may be used as warning agents comprise those which readily dissolve these substances at the lowest temperature occurring in the refrigerating system, and which do not react with them. Thus, alkyl mercaptans may be used with such refrigerants as methyl chloride, ethyl chloride and other halogenated hydrocarbons, propane and other hydrocarbons. 75

Alkyl mercaptans may be used with particularly good results as warning agents in a refrigerating system employing methyl chloride. By means of my invention, persons exposed to concentrations of 0.1% by 80 volume, or even less, of methyl chloride in air are immediately warned of its presence. The invention therefore provides a means for warning persons of concentrations of this substance which are far less than any 85 which would endanger the health in any reasonable period.

If condensed or liquid refrigerant containing 0.5 to 1.0% by weight, of ethyl or butyl mercaptan, is allowed to escape into a closed room so as to build up a concentration of 90 0.05% by volume of gaseous refrigerant in the air, the odor of the mercaptan is very marked; at 0.1% of such odorized methyl chloride in air the odor of the accompanying mercaptan is very strong.

A particularly good feature of mercaptans as warning agents is that the intensity of the odor does not materially decrease on continued exposure; as is the case with many odor- 10

ants. I have found that a person occupying a room, in which a vapor containing a mercaptan is slowly accumulating does not acquire a tolerance for the odor but is as acutely aware of its increased intensity as if he had entered the room from uncontaminated air. A further advantage is that the same warning effect results from leaks from the high and low pressure sides of a compression type refrigerating system, showing that the alkyl mercaptan does not accumulate in any part of the system to such degree as to render its action ineffectual. The mercaptan itself has no harmful effects when used as here specified as warning agents.

Example 1

A compression type refrigerating machine was charged with methyl chloride containing 0.5% by weight of ethyl mercaptan. After the machine had operated two days, measured quantities of the refrigeration vapor were released in a closed room. After the air in the test room had been thoroughly agitated by an electric fan, several persons entered and independently noted their reactions to the odor. In the case of all observers, when the air contained as little as 0.5% methyl chloride gas, the accompanying mercaptan odor was positively identified; and served as a distinct notice or warning. At 1% methyl chloride concentration the mercaptan odor was noted as "strong".

Example 2

The procedure described in Example 1 was carried out with 0.5% butyl mercaptan in methyl chloride. At 0.5% methyl chloride concentration in the air half of the observers noted the accompanying mercaptan odor as "moderate" and the remainder noted "strong"; at 1% methyl chloride concentration the odor of the mercaptan was noted as strong and very strong.

Tests made to determine the effect of ethyl and butyl mercaptans on iron, brass and copper, under conditions similar to those found in operation of a refrigerating system, for instance, dissolved in a refrigerant grade of methyl chloride and under anhydrous conditions, showed that corrosion of these metals by the mercaptans is practically nil.

The suitability of mercaptans for warning agents in refrigerating systems is further shown by the fact that such systems have operated over long periods of time with a refrigerant containing mercaptan with no injury to the machine or other trouble. A compression type refrigerator using as refrigerant, a 2% mixture of ethyl mercaptan in methyl chloride, operated normally and with no trouble for eleven weeks. A test carried out by the method described in Examples 1 and 2 showed no diminution of warning action at the end of this period.

I claim:

1. A composition of matter comprising a refrigerant of the group comprising hydrocarbons and halogenated hydrocarbons containing an alkyl mercaptan in amounts suitable for warning purposes.

2. A composition of matter comprising a refrigerant of the group comprising hydrocarbons and halogenated hydrocarbons containing 0.5% to 2% of ethyl mercaptan.

3. A composition of matter comprising methyl chloride containing an alkyl mercaptan.

4. A composition of matter comprising methyl chloride containing ethyl mercaptan.

5. A composition of matter comprising substantially anhydrous methyl chloride containing 0.5% to 1% of an alkyl mercaptan.

6. A composition of matter comprising substantially anhydrous methyl chloride containing 0.5% to 1% of ethyl mercaptan.

Signed at Niagara Falls in the county of Niagara and State of New York this 26th day of December A. D. 1929.

FRANK J. DOBROVOLNY.
